KEY HOLDER

Charles M. Ballou, Foxboro, Mass., assignor to
Swank, Inc., a corporation of Delaware

Application November 8, 1947, Serial No. 784,783

2 Claims. (Cl. 70—459)

1

This invention relates to a key holder such as may be used for grouping a plurality of keys and holding them in definite relation.

Key holders of this general character have been provided in various ways. Usually some locking device is provided to prevent accidental opening and frequently opening is somewhat difficult for the removal of one or more keys from the group.

One of the objects of this invention is to provide a device which will maintain itself in locked position to hold the keys in grouped relation but which may be easily released for detaching one or more of the keys from the group.

Another object of this invention is to provide an arrangement so that by pressure in one direction upon the finger piece the retaining means will spring to open position so as to permit the removal of one or more keys from the group.

Another object of this invention is to provide an arrangement whereby the resilient means which serve to operate the device will also serve to move the parts into locked relation when the jaws are moved to closed position.

Another object of the invention is to provide a device which may be made simply and in multiple parts which may be easily assembled for completion of the device.

With these and other objects in view the invention consists of detail of certain novel features of construction as will be more fully described and particularly pointed out in the appended claims.

In the accompanying drawings:

Figure 1 is a perspective view of the key holder with keys indicated in dotted lines thereon.

Figure 2 is a partial sectional view of the key holder in closed position.

Figure 3 is a view similar to Figure 2, but illustrating the jaws in open position.

Figure 4 is a perspective view of the latch, and

Figure 5 is a perspective view of the moveable jaw.

In proceeding with this invention, a hollow cap is provided in which one jaw is secured in fixed relation to the cap so as to extend outwardly from the cap generally in a curved or arcuate shape. From the other side of the hollow cap there extends another jaw to abut the free end of the first jaw and which is pivoted in the cap with a spring acting upon it, tending to swing the pivoted jaw about its pivot to move the free ends of the jaws apart. A latch is pivoted in the cap which is under spring action tending to move it into a position to block swinging

movement of the pivoted jaw. The latch has a finger piece protruding thru the cap so as to be accessible for swinging the latch to release the pivoted jaw and permit the spring, which acts upon it, to force the jaw about its pivot to open position.

With reference to the drawings, 10 designates a cap which is of sheet metal construction and may be drawn from a piece of flat stock. This cap provides opposite side walls 11, a top wall 12 extending between the side walls 11, and end walls 13 also extending between the side walls 11. This cap is hollow and the end walls 13 flare outwardly as they extend downwardly from the top wall 12.

Within this hollow structure there is secured a fixed jaw 14 which has one end 15 entering the hollow cap and secured in position by a rivet 16, and also by means of solder to fixedly relate it to the cap. A jaw 17 is pivoted as at 18 in the cap, and has a free end 19 which may swing into abutting relation with the free end 20 of the fixed jaw 14. On the other side of the pivot 18 the end portion 31 of this pivoted jaw is provided with a recess or notch 22 in which there rests a spring 23 which acts between this recess 22 and the corner portion 24 of the cap. The spring tends to swing the jaw 17 about its pivot so as to move the ends 19 and 20 apart.

A latch, designated generally 25 and shown in perspective in Figure 4, is pivoted as at 26 in the cap. A pin 27 extending from the latch serves to center or retain a spring 28 in position against the latch and acts between this portion of the latch and the corner 29 of the cap so as to swing the latch downwardly into the position shown in Figure 2, so that its notch 30 will receive the end 31 of the moveable jaw and prevent the moveable jaw from swinging about its pivot 18 under influence of the spring 23.

There is an opening 36 provided in the top wall 12 of the cap, thru which there extends a finger piece 37 on the latch 25. When the latch is in the position shown in Figure 2, and it is desired to have the jaw 17 swing outwardly, it is merely necessary to press upon this finger piece 37 in the direction shown by the arrow 38 in Figure 3, so as to lift the latch sufficiently to permit the end 31 of the jaw 17 to move past the notch 30 and swing the jaw 17 to open position, at which time the keys shown in dotted line at 39 may be removed from the key holder.

After the key holder is open the latch 25 is released and spring 28 will move it so that portion 32 thereof will engage with the end 31 of the

3

moveable jaw and when this moveable jaw is urged to closed position the latch will be swung about its pivot until the end **31** snaps past the abutment notch **30**.

If it is desired to suspend the key holder then an eye **40** may extend thru the wall **12** and be anchored in this position by a head **41**. A chain **42** may be secured to this eye as indicated in Figure 1.

I claim:

1. A key holder comprising a hollow cap, a jaw member fixed in said cap with a free end extending therefrom, a second jaw member pivoted in said cap and when in closed position having its free end located in close proximity to the end of the fixed jaw member, a spring engaging said pivoted jaw and urging it about its pivot to separate said free ends, and a latch pivoted in said cap and having a finger piece accessible through said cap for locking said pivoted jaw against movement by said spring until manually moved, said latch being spring urged to locking position and provided with a notch to receive the

5

end of said pivoted jaw and so shaped adjacent said notch that movement of the pivoted jaw to closed position swings the latch about its pivot against the action of its spring until the said end lodges in said notch.

2. A key holder as in claim 1 wherein said latch and jaws are in generally the same plane.

CHARLES M. BALLOU.
